UNITED STATES PATENT OFFICE.

CYRUS R. ROBINSON, OF CONCORD, NEW HAMPSHIRE.

HALTER.

SPECIFICATION forming part of Letters Patent No. 297,850, dated April 29, 1884.

Application filed July 30, 1883. (No model.)

To all whom it may concern:

Be it known that I, CYRUS R. ROBINSON, of Concord, Merrimac county, New Hampshire, have invented a new and useful Improvement 5 in Halters, of which the following is a specification.

My improvement relates to a halter to be used for fastening a horse when harnessed without removing the headstall and as a substitute for a hitch-rein. The halters used for this purpose have been clumsy in construction and difficult of application, or else, like the ordinary hitch-rein, insecure, from the fact that they depend on the strength of some portion 10 of the harness not primarily designed for this purpose.

My invention consists in the combination of two strips of leather or other suitable material, fastened together with a ring or eye, D, 20 and with a like ring or eye, C, at the free end of the shorter strap. The shorter of the two straps is made of the proper length to go round the horse's neck sufficiently tight to hold him, and yet not so tight as to choke him. 25 The ring or eye which joins the two parts is of such size that it will not pass through the one at the free end of the shorter piece, but will be stopped when drawn up to it. The longer strap is to tie to a post, or it may be 30 provided with a snapper-hook of a size to go through the ring and through a ring on the post and back and fasten to the eye at the free end of the shorter strap.

The method of using the halter is to throw 35 the shorter end over the horse's neck, pass the longer end through the ring on the free end of the shorter strap, pull it till the two rings are in contact, and then pass the longer end through the ring on the bits, where the hitch-rein is 40 usually fastened, and then tie to a post; or, if

provided with a snapper-hook, pass through a ring on the post and then catch on the ring on the free end of the shorter piece. In this way the horse cannot be choked, as with an old rope-halter, nor can the halter work loose, as the 45 passage through the ring at the bits prevents, and the strain comes chiefly on the horse's neck, instead of at the ring on the bits.

Accompanying this specification, and a part of it, are drawings showing the halter and its 50 mode of construction, and the manner of its application to a harnessed horse.

Figure 2 shows the halter, A being the shorter and B the longer strap, D the ring or eye by which they are united, and C the 55 ring or eye at the free end of the shorter strap. Fig. 1 shows the halter in use with B passed through C and D brought up to and touching C, and B passed through the ring at the bits and hanging down ready for use. 60

When not wanted for use, it may be folded in a small space and laid behind the cushion of the vehicle or under the seat.

Having thus described my invention, what I claim, and desire to secure by Letters Patent, 65 is—

As an improved article of manufacture, a halter or hitching-strap consisting of the two straps A, B and the two rings or eyes C, D, the former being equal in size or larger than the 70 latter, connected and arranged as described, and adapted to be passed around the neck of the animal to be secured, and thence through the bit-ring, as shown and described.

In testimony whereof I hereunto affix my 75 signature in presence of two witnesses.

CYRUS R. ROBINSON.
